UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A UTILITY-TRAY.

15,055.

Specification for Reissued Design. Reissued Mar. 8, 1921.

Original No. 56,335, dated October 5, 1920, Serial No. 334,858, filed October 31, 1919, for 7 years. Application for reissue filed December 3, 1920. Serial No. 428,178. Term of patent 14 years.

To all whom it may concern:

Be it known that I, JOHN BEISWANGER, a citizen of the United States of America, and resident of Steubenville, county of 5 Jefferson, State of Ohio, have invented a certain new, original, and ornamental Design for a Utility-Tray, of which the following is a specification.

In the accompanying drawing I have 10 illustrated a utility tray, constructed in accordance with my invention, the same being of resistive transparent glass.

In the drawing, Figure 1 is a bottom plan 15 view of a utility tray showing my invention.

Fig. 2 is a perspective view looking into the dish.

Having thus described and illustrated my invention, I claim:

The ornamental design for a utility tray 20 substantially as shown and described.

Signed by me at Steubenville, Jefferson county, Ohio, this 24th day of November, 1920.

JOHN BEISWANGER.
